ELECTRICAL AMPLIFIER CIRCUIT

Application filed May 4, 1928. Serial No. 275,178.

This invention relates to electrical circuits, and especially to electrical amplifier circuits, and the like, of the type employing electron or vacuum tubes including an electron emitting element or cathode, an electron receiving anode or plate, and one or more control means which are ordinarily in the nature of grids or the like. Such tubes are commonly designated as audions, triodes, tetrodes, and 5 so forth. The invention is an improvement 10 on the invention described and claimed in the copending application of Lewis M. Hull, Serial No. 207,239, filed July 20, 1927, now Patent 1,672,811; and relates more particularly to an electrical circuit adapted to reduce or suppress certain effects other than desired forward repeater action of the tube, and adapted especially to reduce or suppress 15 certain effects due to the flow of retro-active or regenerative currents arising out of capacitive coupling between the output and input circuits associated with such a tube, this capacitive coupling including particularly 20 capacity between the anode and control means of the tube, and capacity due to connections and circuits associated with the anode and 25 control means of the tube.

Referring now to the drawings, Figure 1 30 represents one specific embodiment of my invention showing its application to a three-electrode tube of standard type. Figure 2 shows a cascaded arrangement employing the circuit of Figure 1. Figure 3 shows one 35 specific embodiment of my invention as applied to a cascaded arrangement including a plurality of four-electrode or "double-grid" tubes. Figure 4 shows a modification of the 40 arrangement of Figure 1. Figure 5 is a graphic representation showing certain effects arising out of the use of my invention in specific cases.

Referring now to Figure 1 of the drawings T_1 represents a three-electrode tube including anode, P , cathode, F , and control means or grid, G . Associated with the grid and cathode of this tube is a tuned input circuit L_0-C_0 , of which the coil L_0 constitutes the secondary of input transformer $L-L_0$, having input terminals 1 and 2. The tuning condenser C_0 may be grounded, as shown, as

by connecting to the negative side of the cathode A suitable "C"-battery, or other means for biasing the grid, may be included in the input circuit, and may if desired be supplied with by-pass condenser C' , or a grid biasing 55 resistance may be arranged in the cathode circuit, as is well understood in this art. The anode circuit of the tube, associated with the anode, P , and cathode, F , includes a coil L_1 and resistive impedance, here shown at R_1 . 60 This resistive impedance may take the form of a separate resistance as shown in Figure 1, or may be embodied in the coil L_1 , as, for example, by winding this coil with resistance wire of suitable size and resistance, as is 65 shown in Figure 4. The resistive impedance of this circuit may, if desired, be made variable or adjustable in order to obtain the desired degree of resistance unbalance, or balance, of the circuit, as will be later explained. 70 A suitable "B"-battery, or other source of direct current, such as a socket-power device or the like, may be included in this circuit as shown, and may be provided with a suitable by-pass condenser C' if desired. The coil L_2 75 is coupled to the coil L_1 in the reverse sense, or the connections to one of these coils are reversed, so that the mutual inductance between them is negative in sign, and is connected in series with a coil L_3 and tuning condenser C_2 , 80 to form a tuned circuit in which the tuning condenser C_2 is connected across coils L_2 and L_3 in series. The coil L_3 is preferably not coupled to either the coil L_1 or the coil L_2 . In practice I frequently prefer to arrange the 85 coil L_3 at right angles to the coil L_2 so as to have substantially negligible electromagnetic coupling therewith. The low potential side of the tuning condenser C_2 may be grounded as shown, a connection thus being formed 90 through ground between the cathode or low-potential side of the input tuning condenser C_0 and the coil L_3 at its junction with C_2 . No separate connection other than that through ground, or the chassis of the amplifier, is necessary, a common ground line being 95 shown in the drawings to represent this connection. The capacitive impedance C_1 is arranged between the control means G and the junction of the coils L_2 and L_3 , in such a way 100

as to permit partial or complete reactance balance of the circuit to reduce effects other than desired forward repeater action of the tube. This capacitive impedance may take the form 5 of a physical balancing condenser C_1 , in which case it may be variable or adjustable as shown, or may include also, or be solely constituted by, so-called "natural" or inherent capacities residing in the circuit or between the elements thereof. The output terminals of the amplifier circuit are indicated at 3 and 4. E_o represents the input voltage of the amplifier circuit (which for the purposes of the present application is measured 10 with the tube unlighted) and E represents the 15 output voltage of the amplifier. The ratio $\frac{E}{E_o}$ therefore represents the voltage amplification, or gain, of the amplifier.

20 Figure 2 represents a multi-stage arrangement in which two amplifier stages each similar to that shown in Figure 1 are arranged in cascaded relation, the tubes being designed as T_1 and T_2 respectively. The coupling 25 system between these tubes includes the primary L_1 , with its associated resistive impedance, R_1 , and the tuned circuit $L_2-L_3-C_2$, the tuning condenser C_2 being connected directly between the grid and cathode of the 30 second tube. The other circuit arrangements 35 may be substantially as before. It is of course understood that in all cascaded or multi-stage arrangements according to my invention, common "A", "B", and "C" batteries may be 40 employed for the several tubes, and may or 45 may not be provided with by-pass condensers and the like, as required. These batteries may of course be replaced by socket-power devices; the "C" batteries may be connected 50 outside the tuned circuit, or may be replaced by biasing resistances; and tubes of the type employing alternating current filaments or heater cathodes, may be employed equally with those illustrated, without departing 55 from my invention.

My invention applies equally, also, to circuits including tubes of the four-electrode or so-called "double-grid" type. One or more such tubes may be employed in circuits according to my invention, and Figure 3 illustrates one specific embodiment of a multi-stage arrangement employing such tubes. The tubes here illustrated are of the type designed for use according to the method which 55 comprises employing the inner grid, or that adjacent the cathode, as the control element, and imparting to the second grid a positive bias, as by a connection to the "B"-battery, or by other suitable means. In the arrangement 60 illustrated, the grids G_2 are given a positive bias by such a connection to the "B"-batteries, which are by-passed by condensers C' . The other circuit arrangements may appropriately be substantially as in Figures 1 and 2.

65 An alternative circuit arrangement, suitable

for use in connection with such "double-grid" tubes, comprises connecting the grid G_2 to the junction of the coils L_2 and L_3 , and thus employing the inherent capacity between grids G_1 and G_2 as the balancing capacity. 70 This inherent capacity may, in certain cases, be augmented by an external balancing capacity connected between grids G_1 and G_2 . In such a circuit arrangement it may, also, be desirable to apply a positive bias to the grid G_2 by means of a separate biasing battery or other means, in which case the coils L_2 and L_3 may be conductively separated by an isolating condenser, as shown in the above-mentioned copending application of Lewis M. 75 Hull. My invention may also be applied to circuits including "double-grid" tubes of the type designed for use according to the method which comprises employing the grid G_2 as the control element, and imparting a positive 80 bias to the grid G_1 .

Figure 4 is a fragmentary diagram of an arrangement similar to that of Figure 1, except that the desired resistance, R_1 , is imparted to the anode circuit by the self-resistance of the coil L_1 . This may be done by winding the coil L_1 with resistance wire. The resistance of the wire to be used depends upon considerations hereafter pointed out, but I may suitably employ various commercial resistance wires for this purpose, for example, "Nichrome" wire. The input circuit, and connections to the grid and cathode (not shown) may suitably be arranged as in Figure 1.

In explaining the operation of my invention, I may state that most balanced or neutralized circuits are designed to reduce or suppress all effects except those due to forward repeater action of the tube. As a result, a typical completely-balanced circuit will normally yield an amplification of the desired input or signal voltage which is determined solely by the amplifier constants of the vacuum tubes and the constants of the associated 100 circuits, substantially unmodified by retroactive or regenerative effects arising from the incidental capacity couplings of the tube. This amplification may appropriately be termed the "repeater amplification" of the 105 stage. It is a fact well established by theory and experiment, however, that in certain types of amplifier circuits, as for instance circuits involving fixed inductances tuned to resonance at different wavelengths by variable 110 condensers, this repeater amplification tends to vary with frequency or wavelength, assuming large values at the shorter wavelengths and smaller values at the long wavelengths, all within the range of a given variable tuning condenser in combination with a given fixed coil. This effect may be undesirable in certain cases. It is, therefore, advantageous not only to suppress retroactive 115 effects which would normally increase the 120

125 130 135

overall amplification by regeneration, and thus produce instability, but, in addition, to further modify the behavior of the stage in such a way that the net amplification, at the shorter wavelengths, is even less than the repeater amplification. This tends to produce more uniform amplification over the wavelength range to which the stage may be tuned. According to my invention the resistance R_1 may serve to accomplish this purpose, in addition to providing a refinement in the conditions of balance in other cases where the realization of full repeater amplification is no detriment and a substantially complete one-way balance is desired.

Without limiting my invention to depend upon any particular theory, I may state that I believe the behavior of resistance R_1 introduced in series with the anode coil of the balanced circuit shown in each of the figures to be as follows:—The circuit may be adjusted, and is subject to reactance balance between the several reactive elements including the tube capacity C_m , the condition for which is specified approximately by the following equation:

$$C_1 = \frac{M_{12}}{L_3} C_m$$

where

C_m represents inter-electrode capacity between anode and control element of the tube, plus stray capacities of leads, connections, etc.

C_1 represents the balancing capacity.

M_{12} represents the mutual inductance between coils L_1 and L_2 .

L_3 represents the self-inductance of the coil L_3 .

This condition, when approximately fulfilled, results in a substantial suppression of all first-order regenerative effects in the stage. The inclusion of resistance R_1 in series with the anode coil L_1 constrains all retroactive

currents returning to the input circuit through capacity C_m to flow also through this resistance. The effect of this is, in general, to modify the input voltage E_o as the circuit $L_2-L_3-C_2$ is tuned to resonance, and to produce either a resistance balance between the various resistive elements of the electrical network, or to provide a non-regenerative controlled resistance unbalance in the presence of a substantial reactance balance where-

55 in the reactive feedback components are substantially balanced out in accordance with the above equation. This resistance unbalance may be employed to reduce the overall amplification below the repeater amplification at shorter wavelengths, since the currents fed back in virtue of the unbalanced resistance component in the circuit are dissipative (i. e. tend to reduce E_o), as contrasted with the currents which are suppressed by the reactance balance because they are regen-

erative (i. e. tend to increase E_o). I have discovered that the degree of this dissipative unbalance due to the presence of R_1 tends to increase with increasing frequency. Thus, for example, the resistance R_1 may be so proportioned as to decrease the short wavelength amplification or gain of the amplifier circuit without appreciably affecting the long wavelength amplification or gain thereof. Alternatively, the resistance R_1 may be so proportioned as to permit the increase to a noticeable or substantial extent of the long wavelength amplification of the circuit without causing loss of stability in the circuit at shorter wavelengths. Thus the resistance R_1 may be proportioned so as to have a differential effect upon the amplifier circuit, reducing the amplification at relatively short wavelengths where excessive amplification is not ordinarily desired, and leaving the amplification at relatively long wavelengths substantially unaffected. Moreover, by a proper adjustment of R_1 , a substantially perfect resistance balance among the components of the electrical network may be obtained, in addition to the reactance balance thereof already described. When such a resistance balance is obtained, the voltage E_o is found to be substantially independent of the tuning of the circuit $L_2-L_3-C_2$.

Certain of the above described effects arising from resistance unbalance produced by various values of R_1 , in one particular circuit, are shown graphically in Figure 5. These

curves illustrate the relation between $\frac{E_o}{E_i}$ (i. e. the voltage amplification) plotted as ordinates and wavelengths plotted as abscissæ.

The curves shown in Figure 5 were taken from experimental data obtained with a specific circuit embodying my invention. The constants of this circuit were approximately at follows:

Tube=UX 226.

G_m (mutual conductance)=1234 micro ohms.

R_p (plate resistance)=6440 ohms.

E_g (grid bias)=−3 volts, to negative side filament.

L_1 =25 turns #36 wire on 1" tube, wound 125 25 turns per inch.

L_2 =92 turns #30 wire on 1 1/4" tube, closely wound.

L_3 =50 turns #30 wire on 11/16" tube, closely wound.

In this particular circuit it will be observed that when R_1 had a value of 132 ohms, the amplification was substantially constant over the wavelength range of 200 to 550 meters.

The foregoing constants apply to one specific circuit embodying my invention, which is of course not limited to these or similar constants.

Thus, in the case of a single or multi-stage amplifier, the stability may be substantially

improved, especially at short wavelengths, by reducing the short wavelength gain, while maintaining substantially the same gain at long wavelengths, the amplification characteristic thereby becoming more uniform; and alternatively, in the case of either a single or multi-stage amplifier, a substantially greater gain at long wavelengths may be obtained, with respect to the long wavelength amplification obtainable with such an amplifier having merely inherent or natural resistance in the anode-cathode circuit, without rendering the amplifier unstable at short wavelengths. In either of these cases the action of the controlled resistance unbalance produced by the use of the resistance R_1 results in an amplifier having substantially more constant or uniform amplification over the wavelength range over which it is designed to operate, than would be obtained with the normal self-resistance of the primary coil L_1 when wound with low resistance wire such as copper, and my invention includes all such cases in which the resistance of the primary circuit is greater than the normal self-resistance of the circuit when L_1 is wound with low-resistance wire.

In my invention the resistance R_1 , operating in one arm of the balancing network, as described above, is not equivalent or analogous to variable plate-circuit resistors of the type which have been heretofore used in non-balanced circuits of the prior art as "volume controls", or in other ways. The operation of such resistors is to reduce the output voltage of the stage by lowering the effective polarizing voltage on the plate. It is a well-known fact that such volume-control resistors, in order to be effective, must have a minimum value of the order of several thousands of ohms, and are not used in connection with a balancing network. According to my invention, the resistance R_1 , which is proportioned in accordance with the other elements of the balanced network, may normally have a value of the order of, say, from about 50 to 200 ohms, although the invention is not limited to this range. This resistance is, in general, negligible as compared with the plate resistance of the vacuum tube, and thus has no appreciable direct effect upon the plate voltage. It serves only to modify the input voltage as described above, through the medium of the currents flowing through the capacity C_m . It therefore has no significance except in connection with a balancing network of the type described.

It is to be understood that my invention includes the production of a controlled resistance unbalance in such an electrical network as is described above, this unbalance being of desired degree and character. It includes also the production of a substantially complete resistance balance in such an electrical network.

The circuit arrangements illustrated in the drawings are merely certain specific embodiments of my invention which is not limited thereto, but which extends to numerous variations and modifications thereof.

Claims:

1. An electrical amplifier circuit comprising, in combination, a vacuum tube including at least an anode, a cathode, and a control grid; an input circuit for said stage associated with said control grid; an anode circuit connected between said anode and cathode and including an output coil and resistive impedance in excess of the normal self-resistance of said coil; a second coil coupled to said output coil; a third coil connected in series with said second coil but having substantially negligible electromagnetic coupling therewith; and a connection between said cathode and said third coil. 70

2. An electrical amplifier circuit comprising, in combination, a vacuum tube including at least an anode, a cathode, and a control grid; an input circuit for said stage associated with said control grid; an anode circuit connected between said anode and cathode and including an output coil wound with resistance wire; a second coil coupled to said output coil; a third coil connected in series with said second coil but having substantially negligible electromagnetic coupling therewith; and a connection between said cathode and said third coil. 85

3. An electrical amplifier stage comprising, in combination, a vacuum tube including at least an anode, a cathode, and a control grid; an input circuit for said stage connected to said control grid; an anode circuit connected between said anode and cathode and including an output coupling coil and resistive impedance in excess of the normal self-resistance of the anode circuit; a second coil coupled to said output coil in the reverse sense; a third coil connected in series with said second coil but having substantially negligible electromagnetic coupling therewith; a connection between said cathode and said third coil; and a balancing capacity connected between said grid and a point between said second and third coils. 100

4. A balanced electrical amplifier circuit including a tube having at least an anode, a cathode, and a control grid; capacitive coupling between said anode and control grid; a coil connected in the anode circuit of said tube; a second coil coupled to said first coil; a third coil constituting with said second coil serially connected elements of a resonant output circuit; a balancing capacitive impedance connected between said control grid and a point in said output circuit, the ratio of said balancing capacitive impedance to said capacitive coupling between anode and control grid being substantially equal to the ratio of the mutual inductance be- 110

between said second coil and said first coil in the anode circuit, to the self-inductance of said third coil, to produce a substantial reactance balance of the electrical network for currents in said resonant output circuit; and means in the anode circuit producing resistive unbalance of said electrical network.

5. An electrical circuit comprising, in combination, an electron tube including at least 10 an anode, a cathode, and a control means; a coil and resistive impedance associated with said anode and cathode; a second coil coupled to said first coil in the reverse sense; a third coil having one terminal connected to 15 said second coil but having substantially negligible electromagnetic coupling with said second coil; a connection including capacitive impedance between said control means and the junction of said second and third 20 coils; and a connection between said cathode and a second terminal of said third coil; said resistive impedance being in excess of the normal self-resistance of the anode circuit and of an order affecting the resistive balance 25 of the network, whereby said electrical circuit may be balanced to control effects other than those due to desired forward repeater action of said electron tube.

6. An electrical circuit comprising, in combination, an electron tube including at least 26 an anode, a cathode, and a control means; a coil and an adjustable resistance connected in series between said anode and cathode; a second coil coupled to said first coil; a third 30 coil having one terminal connected to said second coil but having substantially negligible electromagnetic coupling with said second coil; a connection including capacitive 35 impedance between said control means and the junction of said second and third coils; and a connection between said cathode and a second terminal of said third coil; whereby 40 said electrical circuit may be balanced to control effects other than those due to desired forward repeater action of said electron tube.

7. In an amplifier stage, the combination with an electrical network including an electron tube including at least an anode, a cathode, and a control means; a coil associated 50 with said anode and cathode; a second coil coupled to said first coil in the reverse sense; a third coil having one terminal connected to said second coil but having substantially negligible electromagnetic coupling with said second coil; a tuning condenser connected between the non-common terminals of said second and third coils; a connection including capacitive impedance between said control means and the junction of said second and 55 third coils; and a connection between said cathode and the junction of said third coil with said tuning condenser; of resistive impedance in said anode circuit in excess of the normal self-resistance of said coil and of an order affecting the resistive balance of the

network, whereby said electrical network may be balanced to control effects other than those due to desired forward repeater action of said electron tube.

8. A multi-stage electrical amplifier circuit comprising, in combination, a plurality of electron tubes each including at least an anode, a cathode, and a control electrode; an input circuit associated with the cathode and control electrode of the first of said electron tubes; and coil and resistive impedance in excess of the normal self-resistance of the coil associated with the anode and cathode of said first tube; a second coil electromagnetically coupled to said first coil in the reverse 70 sense and having one terminal connected to the control electrode of the second of said electron tubes; a third coil having one terminal connected to a second terminal of said second coil and a second terminal connected 75 to the cathode of said second tube, said third coil having substantially negligible electromagnetic coupling with said second coil; a connection including capacitive impedance between the junction of said second and third 80 coils and said control electrode of said first tube; a tuning condenser connected between said first terminal of said second coil and said second terminal of said third coil across the control electrode and cathode terminals of 85 said second tube; and a connection to ground common to the cathodes of said first and second tubes and to the junction of said tuning condenser and said third coil.

9. An electrical amplifier circuit comprising, in combination, an electron tube including at least an anode, a cathode, and a control means; an input circuit associated with said control means; a circuit associated with said anode and cathode and including a coil; a second coil coupled to said first coil, and arranged so as to have effectively negative mutual inductance therewith; a third coil connected to said second coil but having substantially negligible electromagnetic coupling therewith; a balancing circuit including capacitive impedance between said control means and the junction of said second and third coils; a connection between said cathode and said third coil; and means comprising 100 the resistive impedance of said circuit associated with said anode and cathode of said tube controlling the resistance balance relation among the elements of said electrical circuit.

10. An electrical amplifier circuit comprising, in combination, an electron tube including at least an anode, a cathode, and a control means; an input circuit associated with said control means; a circuit associated with 105 said anode and cathode and including a coil; a second coil coupled to said first coil and arranged so as to have effectively negative mutual inductance therewith; a third coil connected to said second coil but having sub- 110

stantially negligible electromagnetic coupling therewith; a connection including capacitive impedance between said control means and the junction of said second and third coils; a connection between said cathode and said third coil; and means comprising the resistive impedance of said circuit associated with said anode and cathode of said tube for reducing the short wavelength amplification of said amplifier without substantially affecting the long wavelength amplification thereof.

11. An electrical amplifier circuit comprising, in combination, an electron tube including at least an anode, a cathode, and a control means; an input circuit associated with said control means; a circuit associated with said anode and cathode and including a coil; a second coil coupled to said first coil and arranged so as to have effectively negative mutual inductance therewith; a third coil connected to said second coil but having substantially negligible electromagnetic coupling therewith; a variable condenser connected in series with said second and third coils for tuning the amplifier circuit over a band of wave lengths; a connection including capacitive impedance between said control means and the junction of said second and third coils; a connection between said cathode and said third coil; and means comprising the resistive impedance of said circuit associated with said anode and cathode of said tube for maintaining the amplification of said amplifier circuit at approximately a constant value over a predetermined range of wavelengths.

12. An electrical amplifier circuit comprising, in combination, an electron tube including at least an anode, a cathode, and a control means; an input circuit associated with said control means; a circuit associated with said anode and cathode and including a coil; a second coil coupled to said first coil and arranged so as to have effectively negative mutual inductance therewith; a third coil connected to said second coil but having substantially negligible electromagnetic coupling therewith; a connection including capacitive impedance between said control means and the junction of said second and third coils; and a connection between said cathode and said third coil; the resistive impedance of said circuit associated with said anode and cathode of said tube being of such value that the long wavelength amplification of said amplifier circuit may be substantially increased with respect to that of such an amplifier circuit having merely inherent resistance in said anode-cathode circuit without rendering said amplifier circuit undesirably unstable at short wavelengths.

13. An electrical circuit comprising, in combination, an electron tube including at least an anode, a cathode, and a control

means; an input circuit associated with said control means; a circuit associated with said anode and cathode and including a coil wound with resistance wire; a second coil coupled to said first coil and arranged so as to have effectively negative mutual inductance therewith; a third coil connected to said second coil but having substantially negligible electromagnetic coupling with said second coil; a balancing circuit including capacitive impedance between said control means and the junction of said second and third coils; and a connection between said cathode and said third coil; the resistance of said coil associated with said anode and cathode being of such a value as to effectively control the resistance balance relation among the elements of said electrical circuit.

In testimony whereof, I affix my signature.
